(57) **CLAIM**

The ornamental design for a vehicle canopy frame, as shown and described.

DESCRIPTION

FIG. 1 is a front, top, left side perspective view of a vehicle canopy frame showing my new design;

FIG. 2 is a front, top, right side perspective view thereof;

FIG. 3 is a rear elevation view thereof;

FIG. 4 is a front elevation view thereof;

FIG. 5 is a top plan view thereof;

FIG. 6 is a bottom plan view thereof;

FIG. 7 is a left side elevation view thereof;

FIG. 8 is a right side elevation view thereof; and,

FIG. 9 is a front, top, left side perspective view thereof, shown in a condition of use.

The broken lines illustrate portions of the vehicle canopy frame, which form no part of the claimed design. The broken lines depicting a vehicle canopy in FIG. 9 show environmental structure, which forms no part of the claimed design.
